UNITED STATES PATENT OFFICE.

JACOB J. MAYER, OF CLEVELAND, OHIO.

DESIGN FOR A BASE FOR HYDRAULIC AIR-COMPRESSORS.

SPECIFICATION forming part of Design No. 32,828, dated June 12, 1900.

Application filed March 9, 1900. Serial No. 8,086. Term of patent 14 years.

To all whom it may concern:

Be it known that I, JACOB J. MAYER, a citizen of the United States, residing at Cleveland, in the county of Cuyahoga and State of Ohio, have invented and produced a new and original Design for Bases for Hydraulic Air-Compressors, of which the following is a specification.

The annexed drawing represents the base of a hydraulic air-compressor in side elevation, such base embodying my new design.

The base A is spherical and has a flat equatorial band or zone *a* encircling it. Said band has beaded edges *a'*, which are knurled or chased to present a roughened appearance. The spherical base is mounted upon a foot B

and is connected to the same by a restricted neck C. The foot is domed in the shape of a spherical segment and has a horizontal bottom flange *b*.

20

What I claim is—

The design for a base for hydraulic air-compressors, substantially as described and illustrated.

In testimony that I claim the foregoing as my invention and production I have signed my name this 31st day of December, A. D. 1899.

JACOB J. MAYER.
